See application file for complete search history.

The appearance of the animated graphical user interface sequentially transitions between the images shown in FIGS. 1-9. The process or period in which one image transitions to another forms no part of the claimed design. The wavy broken line perimeter in all FIGS. illustrates a portion of a display screen; the broken line showing of the text within the display screen or portion thereof in all FIGS. is included for the environmental purpose only; the remaining broken lines illustrate portions of a graphical user interface; all broken lines form no part of the claimed design.
